UNITED STATES PATENT OFFICE.

JOHN NELSON, OF OTTAWA, KANSAS.

RAIL-SCARF-FORMING DEVICE.

Application filed May 16, 1921. Serial No. 469,908.

To all whom it may concern:

Be it known that I, JOHN NELSON, a citizen of the United States of America, residing at Ottawa, in the county of Franklin 5 and State of Kansas, have invented certain new and useful Improvements in Rail-Scarf-Forming Devices, of which the following is a specification.

The primary object of the invention is 10 the provision of a machine for easily and quickly forming the opposite ends of a rail from the rolling mill into a scarf joint with bolt holes substantially conforming to the rail joint employed with my wrench mechanism set forth in Patent No. 1,366,587, dated January 25, 1921.

A further object of the invention is to provide a molding machine or press adapted 20 for receiving the end portion of a hot rail-road rail from the rolling mill and forming the same easily and quickly into a complementary joint structure for use in a scarf joint by overlapping the adjacent ends of rails together in track formation.

25 A still further object of the invention is the provision of a machine for complementary forming the opposite ends of a hot rail in the rolling mill whereby an overlapping dove-tailed joint or scarf is formed when the rails are assembled in a track, the formation of both ends of the rails being preferably simultaneous whereby the scarf end of each rail is quickly made after the rails leave the rolls.

30 With these general objects in view the invention consists of the novel combination and arrangement of parts hereinafter more fully described in connection with the accompanying drawings, and in which like 35 reference characters designate corresponding parts throughout the several views.

In the drawings,

Figure 1 is a top plan view of a pair of my machines in their operative positions 45 closed upon the opposite ends of a rail positioned upon the struts after coming from the rolls of the mill, the motors being omitted,

Figure 2 is a transverse sectional view 50 of one of the machines with parts shown in side elevation,

Figure 3 is an end elevation thereof,

Figures 4 and 5 are detail sectional views taken upon lines IV-IV and V-V respectively of Fig. 2,

Figure 6 is a top plan view of an end portion of the machine in its open position,

Figure 7 is a horizontal sectional view taken upon line VII-VII of Fig. 2,

Figure 8 is a vertical transverse sectional view taken upon line VIII-VIII of Fig. 1,

Figure 9 is a side elevation of one end of a rail showing the scarf joint,

Figure 10 is a top plan view thereof,

Figure 11 is a longitudinal sectional view 65 of the same taken upon line XI-XI of Fig. 9,

Figure 12 is a side elevational view of the opposite end portion of the rail.

Figure 13 is a top plan view thereof,

Figure 14 is a central longitudinal sectional view taken upon line XIV-XIV of Fig. 12, and

Figures 15 and 16 are the male and female die members respectively employed with the 75 machine for forming the complementary opposite scarf ends of a rail.

Referring more in detail to the drawings it will be first understood that my invention includes two similar machines 10 adapted for operation upon the opposite end portions of a railway rail such as 11 when the rail is in its red-hot condition mounted upon such supports as struts 12 upon which it passes from the forming rolls of the rolling mill. Die plates 13 and 14 formed with 80 ribs and grooves respectively are designed for use selectively with the machines 10 whereby the opposite sides of the opposite ends of the rail 11 are formed into differently shaped overlapping portions with ribs 15 at one end of the rail 11 and complementary receiving grooves 16 at the opposite end thereof.

Each machine 10 includes a table top 17 with a fixed abutment or anvil 18 adjacent one end thereof and a rectangular frame 19 at its opposite end adapted for mounting a power operating motor 20 thereon. The table top 17 is suitably supported by legs 100 21 having rollers 22 adapted for travel in tracks 23 with the lower ends 24 of the legs 21 formed of dove-tail shape for longitudinally sliding in the grooves 25 of the tracks 23.

The inner face of the anvil 18 has a recess 26 substantially conforming to the shape of one-half of a rail but preferably with a central portion 27 of greater depth than the thickness of a rail web for per-

mitting the molding of a thicker web portion at the scarf joint. A top ledge 28 of the anvil 18 is of sufficient length to overlie the tread 29 of the rail 11 when the end 5 portion of the rail is positioned in the recess 26 as indicated partially by dotted lines in Figures 2 and 8 of the drawings.

- A movable block or jaw 30 slides in side walls 31 between the motor support 19 and 10 the anvil 18 having outwardly projecting ribs 32 slidable upon shoulders 33 in the inner faces of the side walls 31, the jaw 30 having an upstanding rib 34 for limiting the movement of the jaw in closing upon 15 the rail end by engaging the rib 34 with the ledge 28. Retaining plates 35 overlie the ribs 32 and are secured to the side walls 31 by screws 36 whereby the jaw 30 is removably positioned in the machine.
- 20 Two operating screws 37 are mounted through the frame 19 having their outer ends longitudinally slidable through perforations 38 in the adjacent end of the machine while the inner portions of the screws 25 37 are threaded for travel through openings 39 in the inner side of the frame 19. The inner ends of the screws 37 are swiveled as at 40 in the adjacent face of the jaw 30 whereby as will be evident, the simultaneous 30 turning of the screws 37 will forcibly feed the jaw 30 in either direction desired, toward or away from the anvil 18.

A power shaft 41 is journaled through the walls of the frame 19 longitudinally of 35 the machine having a toothed portion 42 forming a long gear within the enclosure 43 of the frame 19. Pinions 44 are secured to the screws 37 within the enclosure 43 in constant mesh with the gear portion 42 of the 40 power shaft 41 while a large gear 45 upon the outer end of the shaft 41 is in constant mesh with a small pinion 46 carried by the drive shaft 47 of the motor 20.

In this manner, the operation of the motor 45 20 controlled by such means as a rheostat 48 imparts great power to the shaft 41 and to the screws 37 permitting the screws to feed the jaw 30 in either direction desired by controlling the direction of 50 the two-way motor 20 it being seen that the pinions 44 may slide longitudinally of the shaft 41 while being rotated through engagement with the gear portion 42 thereof. Rings 49 are preferably carried by the shaft 41 55 at opposite sides of the frame 19 preventing longitudinal movement of the shaft 41 during operation.

The form of scarf ends designed for forming on the rail 11 have been heretofore 60 briefly noted it being also pointed out that the rail end or scarf joint section 50 of the rail 11 has transverse perforations 51 therethrough adapted for receiving a locking bolt while a plurality of arcuate and tapered 65 lugs 52 are formed upon the outer face of the

section 50 adapted for holding the head of the locking bolt against turning when the joint is assembled. The opposite scarf end 53 of the rail 11 has the outer face of its web 54 smooth for seating an expansion 70 spring thereon, the web 54 of the end 53 as well as the web 55 of the end 50 being substantially as thick as the web 56 of the main body of the rail 11.

The inner face of the jaw 30 adjacent the 75 anvil 18 is designed for receiving one of the die plates 13 or 14, the plate 13 being illustrated in use in Figs. 2 and 7 and the plate 14 in Fig. 8 of the drawings. Suitable screws 57 removably secure the plates 13 and 80 14 to the forward face 58 of the jaw 30. Punch members 59 are carried by both of the plates 13 and 14 adapted for punching the perforations 51 through the scarf ends 50 and 53, outlet openings 60 being provided 85 in the anvil 18 permitting the punched out portion of the rails to pass through the anvil and drop beneath the table.

The rail 11 upon the struts 12 as positioned from the rolls is received within the 90 recess 26 of the anvils 18 of the two machines 10 which are moved longitudinally into position for so receiving the opposite ends of the rails by pushing the machines 10 along the tracks 23. When the machines 10 are positioned for use as shown in Fig. 1 with the jaws 30 retracted as set forth in Fig. 6, the motor 20 is started in operation forcing the jaw 30 with its die plate either 13 or 14 into engagement with the end of the 100 rail 11 which is positioned in the machine. The plate 13 is provided with longitudinal ribs 60' as well as the punch members 59 and upon engaging the red-hot rail, the rail is forced into the recess 26 with the web in 105 the recess portion 27 while the ribs 60' form the grooves 16 in the rail end 53 and the punches 59 form the perforations 51 between said grooves. The material from the web 110 which is punched out of the perforations 51 passes through the opening 60 and drops beneath the machine. In a similar manner, the die plate 14 in the machine 10 at the opposite end of the rail is provided with grooves 61 as well as the intervening punch 115 members 59 which upon engaging the heated web of the rail end 50 produces the longitudinal ribs 15. The face of the recess 26 of the anvil 18 in which the jaw 30 employs die plate 14 is provided with depressions 120 62 around the outlet passage 60 for producing the lugs 52 upon the rail web 55 as shown in Fig. 8. At one stamping operation of the jaw 30, the end of the rail that is positioned in the machine is quickly formed into 125 the scarf joint of the predetermined form. The anvil face 55 is preferably inclined as at 63 adjacent the edge of such face where it is contacted by the web 56 of the rail 11 and each jaw 30 has an oppositely inclined 130

portion 64 whereby a thickened web portion 59 is provided at each end of the rail adjacent the scarf joint either 50 or 53. In this manner, the opposite ends of the rail 11 are 5 formed as best shown in Figs. 9 to 14 both inclusive, the webs of the respective ends 50 and 53 being thickened for imparting greater strength to the scarf joint when assembled. The motor 20 being of the reversible type is operated for reversing the direction of rotation thereof when the rib 34 engages the ledge 28 with the device closed upon the work, the reverse movement of the motor 20 retracting the jaw 30 and permitting the finished rail 11 to be removed for repeating the operation upon another rail.

The assembling of two rails in track formation is produced by overlapping the ends 50 and 53 of adjacent rails with the ribs 15 20 of the rail end 50 received in the groove 16 of the rail end 53. Spring locking bolts are then placed through the perforations 51 of the webs 54 and 55 with the heads of the bolts received between the lugs 52 and the 25 springs at the opposite sides of the joint whereby a firm connection is established which will remain locked during all traffic conditions although readily disassembled whenever the occasion requires. The construction of my machine is simple and carries out the object of forming rail ends in scarf arrangement as a commercial proposition and thereby adding only slightly to the initial cost of a rail which greatly reduces the cost of the finished track by eliminating the fish plates, lock nuts and the like.

While the form of my invention herein set forth and described is believed preferable it will be understood that changes may 40 be made therein without departing from the spirit and scope of my invention.

I claim:—

1. A machine for forming scarf joints comprising an abutment member adapted 45 for receiving the end of a rail in heated condition from the forming rolls, a power-driven die adapted for travel toward and away from the rail whereby a scarf joint member is formed thereon, and flange shoulders carried by the abutment member and die for limiting movement toward each other.

2. A scarf joint forming machine comprising a fixed abutment having a recessed 55 face adapted for contact by the end portion of a heated rail, a movable jaw having a limit of travel toward and away from said face adapted for mounting a joint-forming die plate thereon intermediate the upper and lower edges thereof, and said abutment member and movable jaw being constructed for cooperation in limiting movement of the jaw toward the abutment.

65 3. A machine comprising a fixed anvil

having a recessed face adapted for the substantial abutment of one side of a heated rail, the said abutment having an overlying ledge adjacent the ball of the rail when positioned in the machine and a movable mold 70 member adapted for engaging the rail and ledge when the rail is so positioned, whereby the rail end is given a predetermined configuration and movement of the mold toward the anvil is limited.

4. A machine comprising an anvil having a recess substantially conforming to the shape of a rail with an overhanging ledge at its inner edge adapted for receiving the end of a heated rail with the ball of the 80 rail beneath said ledge, a movable mold member adapted for engaging a rail when so positioned provided with a rib in engagement with said ledge when the machine is closed, detachably mounted die plates 85 adapted to be secured to the inner face of the mold member for operation upon the heated rail and means for moving the mold member toward and away from the anvil.

5. A machine comprising an anvil having a recess substantially conforming to the shape of a rail with an overhanging ledge at its inner edge adapted for receiving the end of a heated rail with the ball of the rail beneath said ledge, a movable mold member 90 adapted for engaging a rail when so positioned provided with a rib in engagement with said ledge when the machine is closed, detachably mounted die plates adapted to be secured to the inner face of the mold 95 member for operation upon the heated rail, the anvil having outlet passages from the recessed face thereof and said die plates carrying punching dies adapted for movement through the web of the rail in the machine and into the said passages during the 100 operation of the device.

6. A device of the class described comprising an anvil member having a recessed abutment face, a movable jaw adjacent said 110 face, detachably mounted die plates positionable upon the forward inner face of the jaw adapted for engaging a rail when positioned in the machine and movement limiting means for the jaw at the top of the 115 jaw and anvil.

7. A device of the class described comprising an anvil member having a recessed abutment face, a movable jaw adjacent said face, detachably mounted die plates positionable 120 upon the forward inner face of the jaw adapted for engaging a rail when positioned in the machine, movement limiting means for the jaw at the top of the jaw and anvil, the inner side of the anvil and jaw faces 125 being oppositely inclined adapted for receiving material of the rail web whereby a thickened portion thereof is formed at the inner end of the scarf joint.

8. A device of the class described com- 130

prising an anvil member having a recessed abutment face, a movable jaw adjacent said face, detachably mounted die plates positionable upon the forward inner face of the 5 jaw adapted for engaging a rail when positioned in the machine, movement limiting means for the jaw at the top of the jaw and anvil, the inner side of the anvil and jaw faces being oppositely inclined adapted for 10 receiving material of the rail web whereby a thickened portion thereof is formed at the inner end of the scarf joint, the anvil having outlet passages, and said die plates having punch members forwardly of the jaw adapted 15 for projection through the web of the rail and into said passages whereby bolt-receiving perforations are provided through the rail end.

9. A device of the class described comprising an anvil member having a recessed abutment face, a movable jaw adjacent said face, detachably mounted die plates positionable upon the forward inner face of the jaw adapted for engaging a rail when positioned 20 in the machine, movement limiting means for the jaw at the top of the jaw and anvil, the inner side of the anvil and jaw faces being oppositely inclined adapted for receiving material of the rail web whereby a thickened portion thereof is formed at the inner end of the scarf joint, the anvil having outlet passages, said die plates having punch members forwardly of the jaw adapted for 25 projection through the web of the rail and into said passages whereby bolt-receiving perforations are provided through the rail end, operating screws for the jaw, a shaft operatively geared to said screws and a motor operatively connected to said shaft where- 30 by the jaw is adapted for actuation in either 35 direction at will.

10. A joint-forming machine for rails com-

prising a table having a top substantially upon the level of a rail passing from the rolling mill, a fixed anvil upon the table having a rail-receiving recess and a slideable jaw opposite said anvil adapted for movement toward and away from the anvil, means adapted for limiting the approach of the jaw to the anvil when the rail joint is completed and die plates detachably carried by the jaw adapted for engaging the rail positioned in the machine.

11. A joint-forming machine for rails comprising a table having a top substantially upon the level of a rail passing from the rolling mill, a fixed anvil upon the table having a rail-receiving recess and a slideable jaw opposite said anvil adapted for movement toward and away from the anvil, means 55 adapted for limiting the approach of the jaw to the anvil when the rail joint is completed, die plates detachably carried by the jaw adapted for engaging the rail positioned in the machine, the anvil recess and jaw having 60 oppositely beveled forming portions adjacent the web of the rail whereby the web is thickened adjacent the joint formed in the rail and retaining means for the jaw whereby the jaw is rendered removable at will. 70

12. A machine for forming complementary ends upon railway rails comprising an abutment member for engaging one side of the rail, a jaw member adapted for engaging and forming the opposite side of the rail, a 75 die plate carried by the jaw adapted for engaging the web of the rail, movement-limiting means for the closing travel of the jaw, a motor, a plurality of screws swiveled to the jaw, pinions upon said screws, a shaft 80 geared to said pinions and operative connections between said shaft and motor.

In testimony whereof I affix my signature.
JOHN NELSON.
